UNITED STATES PATENT OFFICE

CHARLES M. BECKER, OF BROOKLYN, NEW YORK

DESIGN FOR A LAMP STAND

Application filed April 14, 1930. Serial No. 35,248. Term of patent 3½ years.

To all whom it may concern:

Be it known that I, CHARLES M. BECKER, a citizen of the United States, and a resident of the borough of Brooklyn, Kings County, city and State of New York, have invented a new, original, and ornamental Design for a Lamp Stand, of which the following is a specification, reference being had to the accompanying drawings, forming a part hereof.

Referring to the annexed sheet of drawings:

I claim:

The ornamental design for a lamp stand, substantially as shown.

CHARLES M. BECKER.
